UNITED STATES PATENT OFFICE.

FRANK H. FOLDEN, OF DES MOINES, IOWA, ASSIGNOR TO MONARCH MANUFACTURING CORPORATION, OF BOONE, IOWA, A CORPORATION OF IOWA.

TROWELING MECHANISM.

1,227,900.

Specification of Letters Patent. Patented May 29, 1917.

Application filed September 16, 1916. Serial No. 120,450.

To all whom it may concern:

Be it known that I, FRANK H. FOLDEN, a citizen of the United States, and a resident of Des Moines, in the county of Polk and State of Iowa, have invented certain new and useful Improvements in Troweling Mechanism, of which the following is a specification.

The present invention relates to machines for molding concrete or other plastic material.

The invention has for its primary object the production of improved mechanism for automatically troweling plastic forms cast in molds.

A further object of the invention is the production in a machine for casting plastic forms, of mechanism including a power-actuated reciprocating carriage to trowel the cast forms.

Still a further object of the invention is the production in mechanism of this class of improved power-transmission and controlling means therefor.

The invention further contemplates an automatic troweling mechanism simple and inexpensive in production and highly efficient in operation.

With these and other objects in view, the invention, consisting in the construction, combination and novel arrangements of parts, will be fully understood from the following description, reference being had to the accompanying drawings, which form a part of this application, and in which like characters of reference indicate corresponding parts throughout the several views, of which,—

Figure 1 is an inside elevation of a machine constructed in accordance with the invention, parts being cut away;

Fig. 2 is a fragmentary side elevation of the same;

Fig. 3 is a horizontal section, taken on the line 3—3, of Fig. 2;

Fig. 4 is an inverted plan of the carriage and parts associated therewith;

Fig. 5 is a transverse section of the same, taken on the line 5—5, Fig. 3;

Fig. 6 is an enlarged side elevation of the laterally movable bearing of the carriage drive-shaft; and

Fig. 7 is a front elevation of the same.

Although I have illustrated and herein-after described the preferred embodiment of the invention, I would not be understood as being limited to the specific structure chosen for illustration for it will be apparent that the various alterations and modifications may be made without departing from the spirit and scope of the invention as defined in the appended claims.

Referring now, to the illustrations, 8, represents the main frame, which may be of any suitable form.

On the main frame is mounted a drive-shaft, 9, actuated by any preferred source of power and carrying a sprocket-wheel, 10, connected by a sprocket-chain, 11, with a relatively large sprocket wheel, 12, mounted on a short shaft, 13, journaled in a suitable bearing, 14, mounted on a cross-member, 15, on the main frame.

The shaft, 13, carries a bevel-gear, 16, intermeshed with a bevel-pinion, 17, mounted on an upright shaft, 18, rotatably supported by the arms of a yoke, 19, the bow of which is freely mounted on the shaft, 13, intermediate the sprocket-wheel, 12, and gear, 16.

From the main-frame depend bars, 20, the lower ends of which are provided with horizontal arms, 21, on the side of one of which is secured a bracket, 22, carrying a horizontal bar, 23, provided with rack teeth on its under side.

On the under sides of the arms are mounted bearings, 24, which slidably support parallel rods, 25, disposed in parallelism with the rack, 23, and interconnected at their ends by cross-members, 26, carrying oppositely disposed parallel racks, 27, positioned below and in parallelism with the rods, 25.

In bearings, 28, on the under side of the rear end portions of the racks, 27, is journaled a transverse shaft, 29, carrying a pinion, 30, intermeshed with the rack, 23, and a sprocket-wheel 31, connected by a sprocket chain, 32, with a sprocket-wheel 33, carried

by a shaft, 34, journaled in suitable bearings, 35, mounted below the forward ends of the racks, 27.

Intermediate the bearings, 35, the shaft, 34, carries a roller 37.

The lower end of the upright shaft, 18, carries a pinion, 38, engageable with either of the racks, 27 and controlled by a laterally movable bearing, preferably comprising a yoke, 39, the arms of which, freely inclose the shaft, 18, and the web of which is formed with a collar, 40, encircling an eccentric, 41, carried by a short shaft, 42, journaled in a bearing, 43, mounted on a cross-member, 44, secured to the supporting arms, 21. The shaft, 42, carries a sprocket-wheel, 45, connected by a sprocket-chain, 46, with a sprocket-wheel, 47, mounted on a shaft, 48, journaled for rotation in one of the supports, 20, and provided with a crank, 49.

In operation, the mold, 50, (shown in Fig. 1), is so positioned with respect to the carriage, that the roller, 37, will trowel the superfluous material from the top of the mold, as the carriage reciprocates.

It is evident that the shaft, 13, drives the upright shaft, and the pinion, 38, constantly, while the machine is in operation.

At opposite ends, the racks, 27, are mutilated or blank, as at 51, to cause automatic disengagement of the racks and the pinion at the ends of the stroke of the carriage. When the carriage reaches the end of its stroke, operation of the crank, 49, causes the eccentric to coact with the collar, 40, to shift the pinion into engagement with the opposite rack to reciprocate the carriage and roller.

It will be observed that the roller is rotated oppositely to its direction of travel, thereby smoothly troweling the forms and forcing the superfluous material ahead of it.

Having thus described my invention, what I claim as new and desire to secure by Letters Patent, is:—

1. In a mechanism for troweling forms of plastic material, a supporting frame, an upright rotatable laterally-movable shaft, a carriage supported by the frame to reciprocate horizontally, and including oppositely-disposed parallel racks positioned on opposite sides of the shaft, a troweling element carried by the carriage, a pinion mounted on the shaft, and means for shifting the shaft laterally to place the pinion in engagement with either rack.

2. In mechanism for troweling forms of plastic material, a supporting frame, an upright rotatable laterally-movable shaft, a carriage supported by the frame to reciprocate horizontally, and including oppositely-disposed parallel racks positioned on opposite sides of the shaft, a pinion on the

shaft, means for shifting the shaft laterally to place the pinion alternately in engagement with the racks to reciprocate the carriage, a roller carried by the carriage to trowel the forms and means actuated by reciprocation of the carriage for rotating the roller.

3. In mechanism for troweling forms of plastic material, a supporting frame, an upright rotatable laterally-movable shaft, a carriage supported by the frame to reciprocate horizontally, and including oppositely-disposed parallel racks positioned on opposite sides of the shaft, a pinion on the shaft, means for shifting the shaft laterally to place the pinion alternately in engagement with the racks to reciprocate the carriage, a roller carried by the carriage to trowel the forms and means actuated by reciprocation of the carriage for rotating the roller oppositely to its direction of travel.

4. In mechanism for troweling forms of plastic material, a supporting frame, an upright rotatable laterally-movable shaft, a carriage supported by the frame to reciprocate horizontally, and including oppositely-disposed racks positioned on opposite sides of the shaft, a pinion on the shaft, means for shifting the shaft laterally to place the pinion alternately in engagement with the racks, said means including a laterally movable bearing on the shaft and having a collar at right-angles to the shaft, and a rotatable shaft having an eccentric encircled by the collar, and a troweling element carried by the carriage.

5. In mechanism for troweling forms of plastic material, a supporting frame, a horizontal reciprocating carriage supported thereby, a troweling roller carried by the carriage, and means for rotating the roller oppositely to its direction of travel, including a rack secured to the frame, a pinion engaged by the rack and mounted on the carriage, sprocket-wheels mounted coaxially with the pinion and roller, and a chain connecting the sprocket-wheels.

6. In mechanism for troweling forms of plastic material, a supporting frame having a horizontal rotating shaft provided with a bevel-gear, a yoke having its bow pivoted on the shaft, a shaft depending rotatably through the arms of the yoke, a bevel-gear on the latter shaft, intermediate the arms of the yoke and intermeshed with said first gear, a troweling carriage supported by the frame to reciprocate horizontally, and including parallel oppositely-disposed racks positioned on opposite sides of the latter shaft, a pinion mounted on the latter shaft to engage the racks, and means for swinging the latter shaft to place the pinion alternately in engagement with the racks.

7. In mechanism for troweling forms of plastic material, a supporting frame, an upright, rotatable, laterally-movable shaft, arms depending from the frame, a horizontally-reciprocating troweling carriage including parallel rods, slidably supported by the arms, and parallel interconnected oppositely-disposed racks positioned on opposite sides of the shaft and in parallelism

with and secured to the rods, a pinion 10 mounted on the shaft and engageable with the racks, and means for moving the shaft laterally to place the pinion alternately in engagement with the racks.

In testimony, whereof, I have hereunto 15 set my hand this 7th day of Sept., 1916.

FRANK H. FOLDEN.
